CLAIM

The ornamental design for a device for aiding insertion of a golf tee, as shown and described.

DESCRIPTION

FIG. 1 is a front perspective view of a device for aiding insertion of a golf tee, showing my new design;

FIG. 2 is a front elevation view thereof;

FIG. 3 is a rear elevation view thereof;

FIG. 4 is a left side view thereof;

FIG. 5 is a right-side view thereof;

FIG. 6 is a top plan view thereof;

FIG. 7 is a bottom plan view thereof; and,

FIG. 8 is a top perspective, exploded view thereof.

1 Claim, 7 Drawing Sheets
